UNITED STATES PATENT OFFICE.

ABRAHAM GULITZ, OF NEW YORK, N. Y.

PRINCESS SLIP.

Application filed February 20, 1926. Serial No. 89,734.

This invention relates to an undergarment and particularly to an improvement on what is known as a princess slip.

An object of the invention is to provide 5 a slip which will fit the figure snugly, especially across the chest, and at the same time be readily adjustable for different sizes of figures.

A further object is to provide a slip which 10 not only fits snugly and is adjustable, but is provided with shields to avoid injury to the texture of the garment.

A further object is to provide a slip having 15 the above mentioned advantages and furthermore capable of being quickly and easily adjusted and removed.

The invention is illustrated in the drawings, of which—

Figure 1 is an elevation of a figure with 20 the garment applied;

Figure 2 is a side elevation of a portion of the garment;

Figure 3 shows the construction of the 25 parts permitting the ready adjustment to the figure the parts in their closed position;

Figure 4 is a section on the line 4—4 of Figure 3;

Figure 5 is a section on the line 5—5 of 30 Figure 3.

The form of the invention shown in the drawings is a preferred form, although it is understood that modifications in the construction and arrangement of the parts and in the character of the materials used may 35 be adopted without departing from the spirit of the invention as set forth in the appended claims.

In order to effect the above mentioned 40 objects I provide the upper edge of the slip with a casing in which is disposed a substantially inelastic tape which, when it is pulled together will hold the upper edge firmly against the body, which in the case of a garment of this sort is across the chest 45 and back. At the upper edge at one side of the garment beneath the arms the garment is split to provide what I choose to call corner flaps. From one edge of one of these flaps an elastic member suitably encased in 50 material similar to that of the body of the garment extends, and is provided on its outer end with fastening means such as hooks and eyes, or snap fasteners, so that it can be fastened to similar cooperating means 55 disposed along the upper edge of the garment on the other corner flap. This adjust-

able fastening means permits the garment to be fitted to different sizes of figures, and by reason of the resiliency of the extending band will hold the tape firmly against the 60 body and thereby cause the upper edge to lie snug.

Extending from one of the corner flaps and lying normally beneath the other at the arm pits is preferably a double fold of material which acts as a shield and by thus lying under the other flap prevents this flap from showing or evidencing injury due to perspiration under the arms. This shield or auxiliary flap can be, along its upper edge, 70 preferably adjustably fastened to the flap under which it lies by means of snap fasteners.

The combination of these elements, therefore, gives an ensemble effect to the garment 75 which very simply achieves the several advantageous objects which have been enumerated above.

The preferred form of the invention as shown in the drawings provides a slip 10 having an upper edge 11 turned over to form 80 a casing for a length of flat, tape 12 which is run through the casing at a point beneath one arm. The upper portion of the garment is slit to provide corner flaps indicated by 85 the numerals 13 and 14, the edges of which are properly constructed to make them strong and prevent unraveling. Extending from one corner flap preferably the flap 13 as shown in Figure 3, and normally lying 90 beneath the other flap 14 is an auxiliary flap 15 which is of two folds of material, as shown in Figure 4, numbered 15 and 16. This flap acts as a shield and lies beneath the flap 14 to prevent the said flap from exhibiting 95 any signs of being soiled due to perspiration. By having a double flap the likelihood of injury being exhibited is reduced to a minimum. Along the upper edge of this flap is a fastening element 17 cooperating 100 with a fastening element 18 along the upper edge of the flap 14.

Extending from the upper corner of the flap 14 is a shirred strip of silk or material 105 similar to that of the garment and within this shirred strip or casing 19 is disposed a length of elastic material 20 to permit this extending band of shirred material 19 to be stretchable. On the outer end of this resilient extension is disposed fastening means 21 110 adapted to cooperate with fastening means 22 or 23 disposed along the upper edge of

the flap 13 at different distances from the meeting edges of the two flaps.

To take the garment off it is merely necessary to unhook or unfasten the fasteners 5 on the end of the resilient band from their cooperating members on the flap 13 and to unfasten the elements 17 and 18.

The upper edge, by having tape extending substantially all the way around will 10 be pulled snugly against the body and will hold it in such position. By means of the resiliency of the band different sizes of figures can be fitted and at the same time maintain a snug relation. By having the shield flap 15 disposed beneath the other the garment can be worn without any exhibition of soiling. These several elements combine to produce an ensemble which is extremely simple and efficient to achieve the objects set forth.

20 What I claim is:

1. A slip which comprises a body portion adapted to fit up under the arms of the wearer having its upper edge under the arm slit to form corner flaps, an auxiliary shield 25 flap extending from one corner flap and lying normally under the other corner flap and

means for holding said shield flap and overlying flap in their cooperative relation, and an elastic strap connecting the free edge of the outer flap with the body of the slip. 30

2. A slip which comprises a body portion slit downwardly from its upper edge to form corner flaps, an auxiliary shield flap extending from one corner flap, means for fastening said shield flap to the other corner flap 35 and elastic means for connecting said corner flaps together.

3. A slip which comprises a body portion having an inelastic upper edge, said body portion slit downwardly from the upper edge to form corner flaps an auxiliary shield flap extending from one corner flap under the other corner flap, fastening means connecting the shield flap to the other corner flap, resilient means extending from the 40 other corner flap and means for adjustably connecting said resilient means to the first mentioned corner flap whereby the upper edge of the slip will be held snugly against the body. 45
